KNIFE WIPER FOR TYPOGRAPHICAL SLUG
CASTING MACHINESFrank C. Frolander, Elizabeth, N. J., assignor to
Mergenthaler Linotype Company, a corporation
of New York

Application February 16, 1945, Serial No. 578,189

4 Claims. (Cl. 199—62)

1

This invention relates to slug casting machines of the general organization represented in U. S. Letters Patent to O. Mergenthaler, No. 436,532, wherein circulating matrices are released from a magazine in the order in which their characters are to appear in print and then composed in line, the composed line transferred to a vertically movable transporter or first elevator which presents it to the mold, the mold filled with molten metal to form a slug or type bar against the matrices which produce the type characters thereon, and the matrices thereafter elevated and returned through a distributing mechanism to the magazine from which they started. At the time the matrices are being elevated and distributed, the cast slug is ejected from the mold and forced between a pair of trimming knives mounted on the vise frame and which dress down the sides of the slug and bring it to the proper thickness.

In these machines, it is necessary at times to vary the vertical position of the first elevator during casting in order to bring about the proper alignment of the matrix characters with the mold slot. For instance, in the use of matrices bearing characters up to 14 pt., the elevator ordinarily is allowed to descend to its lowermost level; whereas, in the use of matrices which characters ranging from 14 pt. to 42 pt., the elevator is arrested at a slightly higher level. In recent years, improvements have been made to adapt the machine to handle matrices with characters above 42 pt., and as high as 60 pt. and more, so that it has been necessary in the use of such matrices to arrest the elevator at a still higher level. For arresting the elevator at its higher levels, the vise frame is ordinarily provided with two pivoted filler pieces or stop members, so constructed and arranged that either may be swung into or out of operative position as desired, their construction and mode of operation being fully described in U. S. Letters Patent to D. S. Kennedy No. 1,595,947.

In these machines, it is also the practice to remove the shavings from the knives after a slug has been trimmed and before the next slug is delivered therethrough, and ordinarily this is accomplished by the use of a knife wiper which is controlled or actuated by the movement of the first elevator, either in its descent or in its ascent. However, when the knife wiper is actuated by the downward movement of the first elevator and the elevator is arrested at its upper casting levels, the wiper will fail to make a complete wiping stroke and, as a result, some of the shavings are not removed from the knife blades

and give rise to the undesirable features which the wiper originally was intended to eliminate.

While arrangements already have been provided whereby the stroke of the knife wiper may be kept constant or uniform regardless of the level at which the elevator is arrested, they require a preliminary manual adjustment or regulation of the parts to condition them for proper functioning during a machine cycle of operation (see the U. S. patent to Burt No. 1,902,434 and the later U. S. patent to Atkins No. 2,088,989).

The present invention contemplates a completely automatic arrangement for the same purpose, which will require no attention whatever on the part of the operator. To this end, the connections between the knife wiper and elevator include a multiplying cam element operative during the downward movement of the elevator to complete the active stroke of the wiper when the elevator is arrested at either of the two upper casting levels, and which is also movable automatically to a neutral position when the elevator is allowed to descend to its normal or lowermost casting level in order that a stroke greater than that required will not be imparted to the wiper. In the preferred embodiment illustrated, the cam element is rotatably mounted on the elevator and controlled by a fixed upright banking member located below the cam element and adapted to turn it to one or another of three different angular positions according to the level at which the elevator is arrested.

In the accompanying drawings, the invention has been shown merely in preferred form by way of example, and obviously many changes and variations may be made therein, which will still be comprised within its spirit. It should be understood, therefore, that the invention is not limited to any specific form or embodiment except insofar as such limitations are specified in the appended claims.

Referring to the drawings:

Fig. 1 is a side elevation of the vise frame and first elevator, showing the knife wiper at the beginning of its stroke and the improved connections between the wiper and the elevator;

Fig. 2 is a side elevation on a slightly enlarged scale and similar to Fig. 1, but showing the position the wiper and multiplying cam element are caused to assume when the elevator is sustained at its normal or lowermost casting level;

Fig. 3 is a top plan view of Fig. 1, showing one of the filler pieces in its active or arresting position;

Fig. 4 is a side elevation similar to Fig. 2 but

showing the position the wiper and cam element are caused to assume when the elevator is arrested at the intermediate casting level;

Fig. 5 is a side elevation showing the relative position of the parts when the elevator is arrested at its uppermost casting level; and

Fig. 6 is a detail front elevation of the cam element and parts adjacent thereto.

After composition, a line of matrices X is delivered to the first elevator A and lowered thereby into casting relation with a mold B, the latter being carried, as usual, by a rotatable disk B¹ (Fig. 2) adapted, first, to advance the mold into contact with the matrix line preparatory to the casting of the slug and, thereafter, to retract and turn the mold from its horizontal casting position to a vertical position directly in front of a reciprocable ejector (not shown). The mold then is advanced a second time into close proximity to a pair of trimming knives C secured to the rear face of a stationary vise frame D, and the slug is then expelled from the mold by operation of the ejector which also serves to force the slug between the knives and beyond the same for delivery to a galley located at the front of the machine. Meanwhile, the elevator A ascends to its highest position where the matrix line is transferred therefrom for distribution, and finally returns to its normal position (Fig. 1) in readiness to receive another composed line.

The elevator A is slidably mounted in the vise frame D and formed with the usual elongated body A¹ and head portion A², which latter overhangs the vise frame and carries the channeled matrix supporting member A³. The head portion A² is also provided with an adjustable banking screw a projecting slightly below the same and through which the elevator is supported from the vise frame at its different casting levels. When casting from matrices bearing characters of a size under 14 pt., the elevator is arrested in its descent at its normal or lowermost level by the direct engagement of the banking screw a with the top surface of the vise frame. However, when casting from matrices bearing characters above 14 pt., it is necessary, as already stated, to arrest the elevator at somewhat higher levels. For this purpose, two filler pieces E and E¹ are employed, the former being fast to a pivot rod e extending transversely across the top of the vise frame and equipped with a knurled knob e¹ for turning it, and the latter being loosely mounted on the rod. In practice, to arrest the elevator at an intermediate level, the filler piece E is moved into active position beneath the head portion A², as shown in Fig. 3; and to arrest the elevator at a higher level, the filler piece E¹, as shown in Fig. 5, is also moved into active position alongside the piece E with its active portions e² and e³ superimposed upon the corresponding active portions e⁴ and e⁵ of the filler piece E. If more detailed information is desired, reference may be had to the Kennedy Patent No. 1,595,947 before mentioned.

As illustrated in the drawings and as embodied in commercial machines, the trimming knives C have associated with them a wiper blade F arranged to move along the edges of the knives, the cleaning stroke of the blade being downward from the position shown in Fig. 1 to that shown in Fig. 2. The blade F is fastened to the upper end of a vertically disposed rod F¹ arranged at the back of the vise frame and properly guided by a bracket F² attached to said frame. To hold the blade out of direct contact with the cutting edges of the knives during its operation, the rod

F¹ is formed with an offset protuberance f adapted to bear against the body portion of one of the knives and slide longitudinally thereon. At its lower end, the rod F¹ is hingedly mounted in a hub portion f¹ of a link member F³ which connects the rod F¹ to a similarly disposed rod F⁴ arranged in front of the vise frame D and slidably mounted in upper and lower fixed brackets G and G¹, respectively. A coiled spring f², surrounding the hub portion f¹ and engaging the rod F¹, holds the protuberance f yielding against the body of the contiguous knife and the wiper blade in the proper wiping position. To facilitate assemblage of the parts, a vertical adjustment of the wiper rod F¹ relatively to its actuating rod F⁴ is permitted by a pair of lock nuts F⁵ mounted on the rod F⁴ and engaging corresponding ears f⁴ of the intermediate connecting member F³.

The active stroke of the wiper rod F¹ takes place in opposition to a compression spring F⁶ surrounding the rod F⁴ and seated upon the lower guide bracket G¹. At its upper end, the spring F⁶ engages an adjustable nut f⁵ on the rod F⁴ and is adapted, through the medium of a spacing collar f⁶ which banks against the bottom surface of the upper guide bracket G, to hold both rods F¹ and F⁴ in their normal or raised position with the wiper blade F flush with the upper ends of the trimming knives.

It so happens that the downward movement of the elevator A from its position of rest, shown in Fig. 1, to its lowermost casting position, shown in Fig. 2, is just sufficient to impart a full active stroke to the knife wiper. It will be obvious, therefore, that unless some expedient were provided to multiply the movement of the wiper when the elevator is arrested at one or the other of the two higher casting levels, the wiper would not complete its active stroke and would fail to clean the lower portions of the knife blades in the manner required.

According to the present invention, the expedient provided for the required purpose includes a multiplying cam element H rotatably mounted on the elevator head A² and arranged to engage, from above, an anti-friction roller f⁷ carried at the upper extremity of the vertical slide rod F⁴. In the preferred embodiment illustrated, the cam element H is formed with a high projecting portion h and with two low concavities h¹, h², the latter being disposed respectively on opposite sides of the projection. A light pull spring H¹, anchored to the elevator head and attached to the cam element, holds the latter yieldingly in its normal position (Fig. 1) against a stop pin h³. When the machine is at rest, the concavity h¹ of the cam element will just clear the roller f⁷ of the rod F⁴, so that an operative connection may be established between the elevator and said rod to impart the active stroke to the knife wiper as the elevator starts its descent to casting position. However, by giving the cam element H a partial turn in a counter-clockwise direction, the rod F⁴ will be forced downwardly in relation to the elevator by the high projection h to multiply the stroke of the wiper F, and if said element is turned sufficiently far to carry the projection beyond the roller f⁷, the rod F⁴ will be permitted to rise under the influence of the compression spring F⁶ so as to neutralize the additional movement imparted to the wiper F as the roller seats in the concavity h².

The operation of the cam element H is effected automatically during the descent of the elevator to casting position by a stationary upright bank-

ing member J, rising from the upper guide bracket G and adapted, as previously stated, to turn the cam element to one or another of three different angular positions according to the level at which the elevator is arrested. As herein illustrated, the member J is formed at the top with a flat banking surface j , located at a predetermined distance above the vise frame D and disposed in the vertical path of a roller h^4 carried by the cam element H. A recess j^1 , cut into the front wall of the banking member, provides the necessary clearance for the projection h of the cam element when the latter occupies the position shown in Fig. 2.

The parts are so arranged that when the elevator A in its descent is arrested at the intermediate casting level by the filler piece E (Fig. 4), the cam element H will be turned by the engagement of the roller h^4 with the banking surface j in the appropriate direction to cam the rod F^4 downwardly in relation to the elevator and thus multiply the corresponding movement of the wiper F sufficiently to complete its active stroke. When the elevator is arrested at the slightly higher casting level by the two filler pieces E and E^1 combined, as shown in Fig. 5, the cam element will be turned in the same way to depress the rod F^4 and again impart the necessary multiplying movement to the wiper. As the elevator starts its ascent after the casting operation and the roller h^4 is carried out of engagement with the banking surface j , the cam element gradually will be restored by the spring H^1 to its original position and permit the roller f^1 of the rod F^4 to remain seated in the concavity h^1 .

At this point, it may be mentioned that while the wiper blade F will not be carried quite throughout the length of the trimming knives C when the elevator is arrested at its uppermost casting level, the additional movement imparted thereto by operation of the cam element H is more than adequate for all practical purposes, it being understood, first, that each slug is usually cast with spaced apart ribs which extend transversely across one of its side faces and are shaved off by the right hand knife as the slug is ejected from the mold in order to bring it to exact size and, second, that when the mold is standing in its vertical position at the ejecting station, the lowermost rib will be located $\frac{1}{8}$ " above the lower end of the slug and at a somewhat greater distance above the lower ends of the trimming knives, so that the thickness of the supplemental filler piece E^1 (actually only $\frac{1}{8}$ ") will not prevent the wiper from cleaning the knives to the extent required.

When the filler pieces E, E^1 are not in use, the cam element H during the descent of the elevator A to its normal or lowermost casting level will be turned by the banking member J to its neutral position shown in Fig. 2. Under these conditions, the full multiplying movement will be imparted to the wiper momentarily, as the high projecting portion h of the cam element passes over the roller f^1 of the rod F^4 , but the original relation of these parts immediately will be restored as the roller f^1 seats in the concavity h^1 . In this way the movements of the wiper blade F will be kept within the limitations of the trimming knives C so as to avoid certain difficulties well known that would otherwise arise prior to the slug casting operation. After the mold recedes from casting position and the elevator rises, the angular position of the cam element H (Fig. 2) will be maintained by the upward pressure of the rod F^4 until

the spacing collar f^2 thereon banks against the guide bracket G. As the elevator continues its upward movement to the transfer station, the cam element will be carried out of engagement with the roller f^1 and permit the pull spring H^1 to swing it back to its normal position against the stop pin h^3 in readiness for a succeeding operation when the elevator again descends with another matrix line to casting position.

Having thus described my invention what I claim is:

1. A slug casting machine equipped with an elevator, means for arresting the elevator at one or the other of two casting levels, a pair of slug trimming knives, a wiper associated with the knives, and automatic means for imparting a full stroke to the wiper regardless of the level at which the elevator is arrested, characterized in that said automatic means include a rotatable cam having high and low portions, a wiper actuating element arranged for engagement with the rotatable cam, and means actuated at each operation of the elevator for rotating the cam to different angular positions to bring a high or low portion thereof into engagement with the wiper actuating element according to the casting level at which the elevator is arrested.

2. A slug casting machine equipped with an elevator, means for arresting the elevator at one or the other of two casting levels, a pair of slug trimming knives, a wiper associated with the knives, and automatic means for imparting a full stroke to the wiper regardless of the level at which the elevator is arrested, characterized in that said automatic means include a rotatable cam carried by the elevator and having high and low portions, a wiper actuating element also carried by the elevator and arranged for engagement with the rotatable cam, and a stationary banking member permanently located in engaging relation to the cam and serving at each operation of the elevator to rotate the cam to different angular positions to bring a high or low portion thereof into engagement with the wiper actuating element according to the casting level at which the elevator is arrested.

3. A slug casting machine equipped with an elevator, means for arresting the elevator at one or the other of two casting levels, a pair of slug trimming knives, a wiper associated with the knives, and automatic means for imparting a full stroke to the wiper regardless of the level at which the elevator is arrested, characterized in that said automatic means include a rotatable cam carried by the elevator and having two low portions and an intermediate high portion, a wiper actuating element also carried by the elevator and arranged to engage in one of the low portions of the cam when the latter is at rest, and a stationary banking member permanently located in engaging relation to the cam and serving at each operation of the elevator to rotate the cam from its position of rest to one or the other of two different angular positions, one with the high portion of the cam in engagement with the wiper element when the elevator is arrested at its upper casting level, and the other with the second low portion of the cam in engagement with the wiper element when the elevator is arrested at its lower casting level.

4. A slug casting machine equipped with an elevator, means for arresting the elevator at one or the other of two casting levels, a pair of slug trimming knives, a wiper associated with the knives, and automatic means for impart-

ing a full stroke to the wiper regardless of the level at which the elevator is arrested, characterized in that said automatic means include a rotatable cam carried by the elevator and having two low portions and an intermediate high portion, a spring for maintaining the cam yieldingly in a position of rest on the elevator, a stop to locate the cam in such position of rest, a vertically movable slide rod also carried by the elevator and connected to the wiper to actuate the same, a spring for holding the rod yieldingly in a raised position, a roller mounted at the upper end of the rod and arranged to engage in one of the low portions of the cam when the latter is in its position of rest, a stationary banking member located in a permanent position in the machine frame, and a roller mounted on the rotatable cam and arranged to be engaged by the stationary banking member at each

10
6

descent of the elevator to rotate the cam from its position of rest to one or the other of two angular positions, one with the high portion of the cam in engagement with the roller on the vertically movable slide rod when the elevator is arrested at its upper casting level, and the other with the second low portion of the cam in engagement with said roller when the elevator is arrested at its lower casting level.

10 FRANK C. FROLANDER.
